UNITED STATES PATENT OFFICE.

GEORGE HOWLETT DAVIS, OF WEST ORANGE, NEW JERSEY.

COMBINED MARKING AND SPOOLING MACHINE FOR MUSIC-ROLLS.

1,074,776.

Specification of Letters Patent.

Patented Oct. 7, 1913.

Application filed January 16, 1911. Serial No. 602,760.

To all whom it may concern:

Be it known that I, GEORGE HOWLETT DAVIS, a citizen of the United States, residing in the town of West Orange, county of Essex, and State of New Jersey, have invented certain new and useful Improvements in Combined Marking and Spooling Machines for Music-Rolls; and I declare the following to be a full, clear, and exact description of same, such as will enable others skilled in the art to which it pertains to make, construct, and use the same.

In my prior Patent No. 968,136, granted August 23, 1910, I have described and illustrated a machine for spooling the sixteen-ply perforated sheets as they have passed through the perforating machines, which latter machines are well known in the art and need no specific description. In the manufacture of perforated music rolls or sheets it is obviously advantageous to perform as much labor upon the multiple sheets while they are held together as it is possible to do so consistent with the kind and character of labor to be put upon them. Many devices have been proposed for placing upon the music sheets the indicating marks, such as the dotted expression mark or line, the sinuous tempo-line, and certain other marks indicating musical expression, while the multiple sheets are held together in the condition in which they leave the perforating machine; but for some one or other reasons these devices have not proved successful in practice and have been discarded with the result that at the present time manufacturers are using the "single" method plan, that is, marking each individual roll separately.

It is the present practice with perforating machines when perforating 65-note music to perforate sixteen separate sheets simultaneously, and when perforating 88-note music to perforate a less number, usually ten sheets simultaneously. It will thus be seen that if each one of the sheets of the cutting is to be marked separately, the work must be multiplied from ten to sixteen times.

It is the purpose of my improvement hereinafter to be described to obviate the necessity of this single marking system and to provide a machine whereby an entire set of cuttings, that is, either ten or sixteen single cuttings may be simultaneously marked in accordance with a single marking model;

this marking may be done as rapidly as the perforating sheets emerge from the perforating machines, or the cuttings may be allowed to accumulate as described in my above named patent, and the trays containing such accumulated cuttings may be placed beneath my new machine and fed thereinto with a result that when the steps of the operation contemplated are completed the entire set of cuttings will not only be provided with the individual expression marks but also wound up in roll form ready for spooling. Thus this improvement mechanically performs the work of from ten to sixteen operatives in far less time and with a greater degree of precision and uniformity. Further, in manufacturing plants where floor space is valuable, the old plan of "single" marking occupies a separate table for each roll to be marked and each table occupies even more space than my improved marking and spooling machine. This, it will be seen is a very decided advantage where floor space is valuable.

In working out my invention I have utilized many of the features illustrated and described in my above named patent, in fact, it may be said that the essential features of the re-spooling machine remain the same and that the marking device has been added thereto.

I will now proceed to describe in detail the mechanism forming my invention.

Figure 1 is a side elevation, partly in section, of my invention. Fig. 2 is a plan view of the same. Fig. 3 is a side elevation, partly in section, of a single marking unit. Fig. 4 is a section on line 4, 4 of Fig. 3. Figs. 5 and 6 are respectively side and rear view of the combined pointer and circuit breaker. Figs. 7 and 8 are respectively end views, partly in section, of the machine, showing the relative position of the marker frame operating shaft, with respect to the other parts of the machine. Fig. 9 illustrates a detail.

The same reference numerals refer to like parts throughout the specification and drawings.

As above indicated my invention has been engrafted upon the structure substantially as illustrated in my above named Patent No. 968,136, to which specific reference is made, for the details thereof in order to avoid repetition. The only material differences reside in the fact that table 16 with its guides

17 and guide spindles or rollers 19, instead of being located above the cross frame are located beneath said cross frame and slightly inclined upwardly toward the tension 5 pulleys 10 and 11. I have also placed the table 20 in a horizontal instead of an inclined position and divided the same as shown in the drawings for a purpose hereafter to be described. I have also provided 10 a series of idler or guide spindles 27, one adjacent to each of the spindles 24, for a purpose hereinafter to be described. Otherwise the details of construction so far as the device illustrated in Patent No. 968,136 is 15 concerned are preserved.

The upper part of the frame 1 is provided with extensions 28, 29, upon which are mounted the guides 30, 31, respectively. These guides consist simply of flat plates 20 and Z plates spanning from one side of the upper timbers of the frame to the other. Within these guides are located the flat plates 32, 33, which form supports for the marking device hereinafter to be described. 25 Secured to the under side of each one of the plates 32, 33, are the racks 34, 35, said racks meshing with the spur gears 36, 37, the latter being mounted upon the ends of a horizontal shaft 38 which extends from one 30 end of the frame to the other, as shown, being mounted in the bearings 39, 40, the latter being located in the cross-timbers of the frame 1. The shaft 38 is provided adjacent to the bearing 40 with a bevel gear 41, which 35 meshes with a similar gear 42, mounted upon a horizontal shaft 43, carried in suitable bearings upon the frame and provided at its outer extremity with a crank 44. It will thus be seen that the turning of the crank 40 44 will cause a rotation of the shaft 38, and a consequent, simultaneous, and uniform movement of the two plates 32, 33, in the guides 30, 31. Secured upon the upper sides 45 of the two plates 32, 33, are the two arch shaped marker supports 45, 46; these supports being formed upon a semi-circle somewhat larger than the spindle supporting frame 2, so that when the plates 32, 33, slide back and forth in their guides 30, 31, the 50 marker supports 45, 46, are compelled to move laterally or in a direction parallel to the axes of the spindles 24. Located between the two supports 45, 46, at intervals throughout their length, so as to be adjacent to the 55 spindles 24, are the marking devices which I will now proceed to describe. Inasmuch as all of the marking devices are alike, a description of a single one of them is deemed sufficient.

60 Each marking device consists of a solenoid magnet mounted upon a U shaped bracket 47, the legs of which are secured respectively to the plates 45, 46, by means of the bolts 48 and wing nuts 49, said bolts 65 passing through slots 50 in the plates 45, 46.

so that the bracket 47 may be adjustably secured to the plates 45, 46. Secured to the underside of the bracket 47 is the solenoid magnet 51 having the central axial rod 52 passing therethrough, said rod being provided at its upper end with an armature 53. Beneath the head of the armature I locate a small coil spring 54, the tendency of which is to hold said armature away from the end or pole of the magnet, the distance, of course, being limited by means of the collar 55 upon the rod 52 just outside the lower end of the magnet. I mount a rotatable dotting wheel 56, upon a short stub shaft 57, which is journaled in the lower end of the rod 52. The rotation of the dotting wheel is effected by the means of a ratchet wheel 58 and a pair of spring pawls, one of which, 59, is secured to the lower end of the magnet, while the other pawl, 60, is secured to the rod 52, as clearly shown in Fig. 3. It will thus be seen that the reciprocation of the rod 52 under the influence of the magnet 51 will cause a step by step rotation of the dotting wheel 56, inasmuch as the pawl 59 will engage successively the teeth of the ratchet wheel 58 at each reciprocation while the pawl 60 will serve to prevent excessive rotation or rotation beyond a single step. Secured adjacent to the dotting wheel in any 90 convenient manner, as by means of the arms 61, is the rotating inking wheel 62 with its periphery bearing upon the dotting projections of the wheel 56. It should be understood that the inking wheel 62 freely rotates in contact with the wheel 56 so as to provide a fresh supply of ink for each one of the dotting projections in succession.

From a reference to Fig. 3 it will be noted that the idler or guide spindles 27 are mounted in the circular frame 2 in a position between adjacent take-up spindles 24, and that the perforated rolls pass over such idler or guide spindles 27 before being wound upon the spindles 24. The dotting 105 wheel 56 together with a dotting apparatus is located upon the frame 45, 46, in a position so as to be immediately adjacent to the periphery of the spindles 27, in order that the dotting projections on the wheel 56 may 110 mark the perforated rolls 23 just as they pass over the idler spindles 27.

In practice a marking model perforated roll 63 is provided upon which the exact line to be duplicated upon the perforated rolls is 115 carefully delineated. This marking model is in all respects a pattern, having note perforations of the same note value as are found in the perforated rolls and it is used as a guide for duplicating either the expression-line or tempo-line upon the completed 120 perforated roll. This marking model must therefore be matched up with the set of perforated rolls 23 at as nearly as possible the time said rolls are threaded into the machine. 130

This may be done by laying such roll with its model line face downward upon the entire set of cuttings which are then located in the tray 22, as clearly shown in Fig. 1. The marking model, however, is not threaded through the machine in the same manner as the remaining perforated rolls 23. Being upon the top or outside of all the other perforated sheets this roll 63 is carried over a pair of take-up rolls 64, 65, thence across a table 66 and around a guide roll 67 to a take-up spindle 68, the latter being driven by the same power as the other spindles 24 and at identically the same rate of speed.

In actual practice the marking model is usually a cutting made from some master from which all of the perforated sheets to be marked have been cut and the marking model may or may not perfectly register with the perforated sheets to be marked so far as the perforations go. The matching up heretofore referred to is, therefore, done as nearly as it is possible to match up the perforations of the marking model with the perforations in the sheets to be marked. This deviation of registry between the marking model and the perforated sheet is common, and may be accounted for by a slight change in the feed of the perforating machine at different times, or variations in the quality or texture of the paper resulting in greater or less degrees of expansion or contraction under atmospheric changes. Some means must, therefore, be provided for adjusting the marking model back into registry with the perforated sheets as they travel through the machine. This deviation is observed by the operator from the location of the pointer, hereinafter referred to, with respect to some particular perforation in the marking model and the position of the dotting wheel 56 with respect to the corresponding perforation in the perforated sheets 23, as they pass over the idler spindle 27. The means for adjusting this registry will now be explained. As heretofore stated this marking model 63 is laid with its model line face downward upon all the rest of the sheets 23 before said sheets are threaded into the machine, so that when it is threaded into the machine its model line will appear face upward upon the table 66. Inasmuch as this line is to be followed as a model or pattern from which all of the other rolls are to be marked, it is necessary that the particular point in the line which is to be followed by a pointer must be somewhat advanced, and to provide for this advance the two take-up rolls 64, 65, are interposed so that the pointer hereinafter referred to will be located just over a point in the line in the marking model which will correspond exactly to the point in the perforated sheets 23 which will pass over the idler spindles 27. Some means must now be provided for ad-

justing these take-up rolls so that the model line and the note perforations will correctly register both in the marking model and in the perforated sheets 23 as the latter are marked. This adjustment is provided in the following manner: 69 represents the bearings for the take-up roll 65, the journals of which extend laterally outside of said bearings and have mounted thereon the links 70, one of which, namely, upon the front side of the machine, extends into an arm 71 which engages a ratchet rack 72 for holding said arm 71 in any desired position. It will thus be seen that when the arm 71 is moved around the rack, the link portion 70 thereof, will carry the take-up roll 64 with it and thereby take up more or less of the length of the marking model 63, so as to bring the particular point in the model line on the marking model above the table 66.

I will now proceed to describe the pointer which is designed to follow the model line upon the marking model.

Upon reference to Fig. 1, it will be noticed that the take-up spindle 68 is spaced away from the last one of the take-up spindles 24. Projecting through this space is the arm 72, the upper end of which is secured to the frame plate 46, as shown, the forward end of said arm 72 being bent downwardly so as to bring its lower end to a point slightly above the table 66. Secured to the lower end of this arm 72 is a swiveled wheel 72¹, somewhat offset from the axis of the lower end of the arm 72 in the manner of the ordinary bed caster. This wheel is permitted to contact with the marking model as the same travels over the table 66, and in order to provide for easy swiveling I have mounted the wheel shank 73 upon ballbearings, as shown; any convenient style of ballbearings which will provide for easy turning of the shank 73 upon the lower end of the arm 72 may be used.

The wheel 72¹ is of peculiar construction. It is comparatively broad faced, having a groove in the center thereof in which is mounted a rubber ring 74, and upon each side of said ring in the face of the wheel I provide at uniform intervals insulation 75, 115 as shown. Bearing upon the face of the wheel 72¹ and on either side of the rubber ring 74, are the two contact springs 76, which are separately mounted upon a lateral projection 77 with the insulation 78 interposed to provide against cross-circuiting. From each of the contact springs 76, 76, respectively are led circuit wires 78¹, 79, which wires are led along the arm 72; one of them leading to one pole of a battery or other source of electric power 80 through a single pole switch 81, and thence along the frame plate 46, adjacent to the series of magnets 51. The other wire 78¹, is led along the plate 46 parallel to the first named wire. 130

Short shunt wires 82, 83, are led from the wires 78¹, 79, to each of the magnets as clearly shown in Fig. 3.

From a reference to my above named Patent No. 968,136, it will be seen that the perforated sheets 23 are simultaneously wound upon the spindles 24 by turning the crank upon the shaft 6, the motion being communicated to all of the spindles through the belt 9. As shown in the drawings this belt 9 passes over the corresponding pulley which drives the take-up spindle 68. Consider now that the machine is now all threaded up as clearly illustrated in Fig. 1, and that it is desired to mark each one of the rolls 23 in accordance with the line on the marking model 63. The operator will first manipulate the crank 44, and thereby bring the frame plates 45, 46, into a position so that the wheel 72 will be immediately over the model line on the marking model 63. The operator then with the crank 44 in the one hand to manipulate the position of the arm 72 to follow this line, grasps the crank on the shaft 6 with his other hand, rotates said crank to wind up the perforated rolls 23 upon their respective spindles and also the marking model sheet 63 upon its spindle 68. As this marking model 63 travels over the table 66 the operator manipulating the crank 44 will cause the wheel 72¹ to follow the model line on the marking model 63, but inasmuch as the rubber ring 74 causes the rotation of the wheel 72¹ as the marking model travels under such wheel, the electric circuit through the series of magnets will be opened and closed as the metallic points in the wheel 72¹ and the insulation 75 pass under the contact springs 76, 76. This will cause a simultaneous make and break in the circuit and a consequent simultaneous actuation of each of the magnets 51, to cause the dotting wheels 56 to be reciprocated against the perforated sheets 23 as they pass over the idler spindles 27. Any deviation in the line on the marking model will be carefully followed by the operator manipulating the crank 44, so that as the pointer 72² follows the line it is clear that the dotting wheels 56 will be moved parallel to the axes of the spindles 24, and the reciprocation of such dotting wheels through the means of the magnets 51 will cause an exact duplication upon the entire set of perforated rolls 23, of the line upon the marking model 63.

All of the features relative to the uniform tension in the perforated rolls 23 referred to in my prior Patent No. 968,136, are maintained in the structure just described and when the rolls 23 are completely wound up as is described by my present improvement they are also completely marked in accordance with the marking model.

I have shown this marking device as being a separate and distinct machine from a

perforating machine, but I wish it to be understood that the set of perforated rolls 23, instead of being stored up in the trays 22, as illustrated, in Fig. 1, may be taken directly as they emerge from the perforating machine. This is in fact the better way of utilizing this improvement for the reason that as the set of sheets 23 emerge from the perforating machine and are held under uniform tension there can be no shifting of the individual rolls 23 among themselves and the result of the marking will be exactly uniform throughout. As an example of such perforating machine I wish to refer to my prior Patent No. 659,053, granted October 2, 1900, wherein I have shown the complete perforating machine for perforating music sheets, either singly or in gangs.

In my Patent No. 747,687, dated December 22, 1903, I have shown a device for simultaneously marking a plurality of rolls from a single marking model. In practice the machine of this patent operated admirably upon a limited number of sheets which however had to be separately spooled prior to the marking operation. With an entire cutting of from ten to sixteen rolls, however, two or three operatives and sometimes more, are required to keep all of the separately spooled rolls in correct registry with the marking model so that the zig-zag or sinuous line to be duplicated upon the perforated music sheets would register correctly with corresponding note slots. My present device obviates all these difficulties and makes it possible for a single operative to accurately mark an entire cutting of sixteen rolls, but at the same time spool the entire set of sheets as they leave the perforating machine. The perfect registry of all of the sheets of the cutting is maintained by keeping them in gangs with their edges clipped together by ordinary paper clips as they emerge from the perforator when, of course, the entire gang must be in exact registry. These clips are removed prior to the passage of the gangs of sheets between the tension rolls, 10, 11, and the registry is maintained by these tension rolls.

The arc upon which the frame 2 is struck is not an exact circle, but approaches the circle very closely. It is really a double involute of the two rolls 10, 11, so that the distances from the point between said rolls (their point of tangency) where the sheets 23 begin to separate or radiate to the point where they pass over the idler spindles 27, are the same for all of the sheets. It will thus be seen that the registry of the note slots having been maintained up to the tension rolls 10 and 11, such registry as the sheets pass over the idlers 27, will be preserved, and since all of the dotting wheels are actuated in unison the resulting zig-zag or sinuous line will be identical upon all of

the sheets, and correctly register in its deviations with the note slots of said sheets. The adjusting take-up 64, 65, as above described, provides for the adjustment of the registry of the perforated sheets 23 with the marking model 63. It will thus be seen that I am able by a single machine, handled by a single operative, to accomplish what has heretofore required from four to sixteen operatives to accomplish, while the work done is much more accurately and quickly done.

I claim:

1. In a device of the class described the combination of a plurality of parallel spindles, a stationary frame in which said spindles are mounted, arc shaped means for simultaneously rotating said spindles, means for maintaining a uniform tension in the materials to be wound upon said spindles, and a separate marking device for and located adjacent to each of said spindles for simultaneously and uniformly marking the materials to be wound upon said spindles.

2. In a device of the class described the combination of a plurality of parallel spindles, an arc shaped frame in which said spindles are mounted, means for simultaneously rotating said spindles and means for simultaneously and uniformly marking the materials to be wound upon said spindles during the winding operation.

3. In a device of the class described, the combination of a plurality of spindles, an arc shaped frame in which said spindles are mounted, means for simultaneously and uniformly marking the material to be wound upon each of said spindles during the winding operation.

4. In a machine for spooling and marking perforated music sheets, the combination of a plurality of spindles, an arc shaped frame in which said spindles are mounted, means for rotating all of said spindles at the same speed, a perforated marking model sheet having a zig-zag or sinuous line thereon for indicating musical effects to be produced in playing, a pointer for following said line and means for simultaneously marking duplicate lines upon each of the perforated music sheets as the same are wound upon said spindles, said means being governed or controlled by the movements of said pointer.

5. In a machine for marking and spooling perforated music sheets, the combination of a plurality of parallel spindles, an arc shaped frame upon which said spindles are mounted, means for simultaneously rotating all of said spindles at the same relative speed, and means for applying a zig-zag or sinuous line to each of said music sheets as they are wound upon said spindles.

6. In a machine for simultaneously marking and spooling a plurality of perforated

music sheets, the combination of a plurality of spindles arranged in the arc of a circle, means for rotating said spindles, one for each perforated sheet, and means for applying a zig-zag or sinuous line upon each of said sheets, as they are wound upon said spindles.

7. In a machine for simultaneously marking and spooling a plurality of perforated music sheets, the combination of a plurality of spindles arranged in the arc of a circle, means for rotating said spindles, one for each perforated sheet, a marking device for each sheet, said marking devices being located respectively adjacent to said spindles and means for actuating all of said marking devices to apply a zig-zag or sinuous line respectively to each of said sheets as the same are wound upon their respective spindles.

8. In a machine for simultaneously marking and spooling a plurality of perforated music sheets, the combination of a plurality of take-up spindles arranged in the arc of a circle, means for rotating said spindles, a separate marking device for each sheet, located adjacent to and movable parallel to the axis of each take-up spindle, and means for actuating each of said marking devices to move laterally across the faces of said perforated sheets and to apply a zig-zag or sinuous line to each of said sheets, as the same are respectively wound upon said spindles.

9. In a machine for simultaneously marking and spooling a plurality of perforated music sheets, the combination of a plurality of spindles, arranged in the arc of a circle, means for rotating said spindles, one for each music sheet, a separate marking device for each sheet, an arc shaped frame or support for all of said marking devices, means for moving said frame or support parallel to the axes of said spindles, and means for simultaneously actuating all of said marking devices to apply a sinuous or zig-zag line upon each of said music sheets as they are wound upon said spindles.

10. In a machine for simultaneously marking and spooling a plurality of perforated music sheets, the combination of a plurality of spindles arranged in the arc of a circle one for each of said sheets, a perforated marking model sheet having a zig-zag or sinuous line delineated thereon, a rotating spindle for said marking model sheet, means for simultaneously rotating all of said spindles to wind the respective sheets thereon, and means for marking a duplicate of the zig-zag or sinuous line of the model sheet upon each of the perforated music sheets during the winding of all of said sheets upon their respective spindles.

11. In a machine for simultaneously marking and spooling a plurality of perforated

- music sheets, the combination of a perforated marking model sheet having a zig-zag or sinuous line delineated thereon, a plurality of simultaneously rotating spindles arranged in the arc of a circle, and means for winding said sheets thereon, a pointer for following said zig-zag or sinuous line as the same passes under said pointer, a plurality of marking devices, one for each music sheet, connections between said pointer and marking devices whereby they are moved in unison parallel to the axes of said spindles, and means for actuating said marking devices whereby a duplicate of said zig-zag or sinuous line is delineated upon each of said perforated music sheets as they are wound upon said spindles. 10
12. In a machine for simultaneously marking and spooling a plurality of perforated music sheets, the combination of a perforated marking model sheet having a zig-zag or sinuous line delineated thereon, a plurality of spindles having parallel axes and means for rotating said spindles for winding all of said sheets into roll form, a laterally movable pointer for following said line as it passes under said pointer, a plurality of electro-magnetic marking devices, one for each perforated music sheet, connections between said pointer and said devices to cause them to move laterally across the face of their respective sheets in unison, and electrical connections between said pointer and each of said marking devices to cause the latter to duplicate said zig-zag or sinuous line upon each of said perforated music sheets as they are wound upon their respective spindles. 20
13. In a machine for simultaneously marking and spooling a plurality of perforated music sheets, the combination of a perforated marking model sheet having a zig-zag or sinuous line delineated thereon, a plurality of rotating parallel spindles mounted in a semicircular frame, means for winding all of said sheets thereon, a rigid supporting frame for said spindles, a plurality of marking devices, one for each perforated music sheet, a pointer for following said zig-zag or sinuous line, a semicircular supporting frame upon which said marking devices and pointer are rigidly mounted and means for moving said latter frame in a path parallel to said spindles to permit said pointer to follow said line as it passes under said pointer, and thereby cause said marking devices to delineate a duplicate line upon each of said perforated music sheets. 30
14. In a machine for simultaneously marking and spooling a plurality of perforated music sheets, the combination with a perforated marking model sheet having a zig-zag or sinuous line delineated thereon throughout its length, means for simultaneously winding all of said sheets upon spindles, an electro-magnetic marking device for each of said perforated music sheets, a pointer for following said zig-zag or sinuous line upon the marking model, means connecting all of said marking devices and said pointer to cause the same to move in unison, and electrical connections between said pointer and said marking devices whereby the latter are actuated to duplicate said sinuous or zig-zag line upon each of said perforated music sheets as the same are wound upon said spindles. 40
15. In a machine for marking and spooling gangs of perforated music sheets, as they leave a perforating machine, the combination of a plurality of parallel spindles arranged in the arc of a circle, means for simultaneously rotating all of said spindles at the same speed, a pair of tension rolls at the center of said arc, between which a gang of perforated music sheets is led to said spindles, a perforated marking model sheet associated with said gang of perforated music sheets, said model having traced throughout its length a zig-zag or sinuous line, means for tracing a duplicate of said line upon each of said perforated music sheets as they are respectively wound upon their spindles. 50
16. In a machine for spooling and marking perforated music sheets, the combination of a plurality of parallel spindles, an arc shaped frame upon which said spindles are mounted, means for rotating all of said spindles at the same speed, a perforated marking model sheet having a zig-zag or sinuous line thereon for indicating musical effects to be produced playing, a pointer for following said line, means for simultaneously marking duplicate lines upon each of the perforated music sheets as the same are wound upon said spindles, said means being governed or controlled by the movements of said pointer and means for adjusting said marking model into registry with said perforated music sheets. 60
17. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 70
18. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 80
19. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 90
20. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 100
21. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 110
22. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 120
23. In a machine for marking perforated music sheets, the combination of a perforated marking model sheet having a zig-zag or sinuous line thereon, a pair of spindles, means for winding a perforated music sheet upon one of said spindles and said marking model sheet upon the other spindle, a pointer for following said line, an electrical marking device located adjacent to the first named spindle, electrical connections between said pointer and marking device, whereby as said pointer is caused to follow said line as it passes under said pointer, said marking device will be caused to produce a duplicate line upon the perforated music sheet as the same is wound upon the first named spindle, and means for adjusting said marking model into registry with said perforated music sheet. 130

18. In a machine for simultaneously marking and spooling a plurality of perforated music sheets, the combination of a plurality of rotating-spindles one for each of said sheets, a perforated marking model sheet having a zig-zag or sinuous line delineated thereon, a rotating spindle for said marking model sheet, means for simultaneously rotating all of said spindles to wind 10 the respective sheets thereon, electro-magnetic means for marking a duplicate of the zig-zag or sinuous line of the model sheet upon each of the perforated music sheets during the winding of all of said sheets, 15 upon their respective spindles, and means for adjusting said marking model into registry with said perforated music sheets.

19. In a machine for simultaneously marking and spooling a plurality of perforated 20 music sheets, the combination of a perforated marking model sheet having a zig-zag or sinuous line delineated thereon, a plurality of simultaneously rotating spindles for winding said sheets thereon, a pointer for 25 following said zig-zag or sinuous line as the same passes under said pointer, a plurality of electro-magnetic marking devices, one for each music sheet, electrical connections between said pointer and marking devices 30 whereby they are moved in unison parallel to the axes of said spindles, means for actuating said marking devices whereby a duplicate of said zig-zag or sinuous line is delineated upon each of said perforated music 35 sheets as they are wound upon said spindles, and means for adjusting said marking model into registry with said perforated music sheets.

20. In a machine for simultaneously marking and spooling a plurality of perforated 40 music sheets, the combination of a perforated marking model sheet having a zig-zag or sinuous line delineated thereon, a plurality of spindles having parallel axes for 45 winding all of said sheets into roll form, a laterally movable pointer for following said line as it passes under said pointer, a plurality of marking devices, one for each perforated music sheet, connections between said 50 pointer and said devices to cause them to move laterally across the face of their respective sheets in unison, electrical connections between said pointer and each of said marking devices to cause the latter to duplicate 55 said zig-zag or sinuous line upon each of said perforated music sheets as they are wound upon their respective spindles, and means for adjusting said marking model into registry with said perforated music 60 sheets.

21. In a machine for simultaneously marking and spooling a plurality of perforated music sheets, the combination of a perfo-

rated marking model sheet having a zig-zag or sinuous line delineated thereon, a plurality of rotating parallel spindles mounted upon a semi-circular frame, means for winding all of said sheets thereon, a rigid supporting frame for said spindles, a plurality of marking devices, one for each perforated 65 music sheet, a pointer for following said zig-zag or sinuous line, a semi-circular supporting frame upon which said marking devices and pointer are rigidly mounted, means for moving said latter frame in a path parallel 70 to said spindles to permit said pointer to follow said line as it passes under said pointer, and thereby cause said marking devices to delineate a duplicate line upon each 75 of said perforated music sheets, and means 80 for adjusting said marking model into registry with said perforated music sheets.

22. In a machine for simultaneously marking and spooling a plurality of perforated music sheets, the combination with a perforated marking model sheet having a zig-zag or sinuous line delineated thereon throughout its length, means for simultaneously winding all of said sheets upon spindles a marking device for each of said perforated 85 music sheets, a pointer for following said zig-zag or sinuous line upon the marking model, means connecting all of said marking devices and said pointer to cause the same to move in unison, electrical connections between said pointer and said marking devices whereby the latter are actuated to duplicate said sinuous or zig-zag line upon each of said perforated music sheets as the same are wound upon said spindles, and 90 means for adjusting said marking model into registry with said perforated music 95 sheets.

23. In a machine for marking and spooling gangs of perforated music sheets, as they 105 leave a perforating machine, the combination of a plurality of parallel spindles arranged in the arc of a circle, means for simultaneously rotating all of said spindles at the same speed, a pair of tension rolls at the center of said arc, means for guiding a gang of perforated music sheets between said tension rolls to said spindles, a perforated marking model sheet associated with said gang of perforated music sheets, said model having traced throughout its length a zig-zag or sinuous line, means for tracing a duplicate of said line upon each of said perforated music sheets as they are respectively wound upon their spindles, and means for 110 adjusting said marking model into registry with said perforated music sheets.

G. HOWLETT DAVIS.
